HAMMER MILL HAVING A RIGID, REMOVABLE
ECCENTRICALLY DISPOSED SCREEN
James G. Bryant, ½ Bryant Engineering Company,
1504 16th Ave., Port Huron, Mich.
Filed Oct. 29, 1962, Ser. No. 233,634
12 Claims. (Cl. 146—79)

This invention relates to a hammer mill.

It is an object of this invention to provide a hammer mill which has a relatively large capacity in relation to its size.

A further object of the invention is to provide a hammer mill provided with a screen that does not require flexing for its removal and replacement so that the screen can be formed of a heavy rigid material and is therefore adaptable for grinding whole ears of corn, corn cobs and other relatively heavy materials.

A further object of the invention is to provide a hammer mill incorporating the above described features and at the same time enabling the screen to be safely removed and replaced with another screen without stopping the operation of the hammer mill.

In the drawings:

FIG. 1 is a perspective view of a hammer mill according to the present invention.

FIG. 2 is a sectional view along the line 2—2 in FIG. 1.

FIG. 3 is a sectional view similar to FIG. 2 and showing the position of the screen at two progressive positions of removal.

FIG. 4 is a sectional view along the line 4—4 in FIG. 2 and showing the cradle structure for the screen.

Referring to FIG. 1, the hammer mill of the present invention comprises a housing 10 in which is journalled a rotor 12, the rotor being rigidly secured to a shaft 14 which is journalled on the housing by means of bearings, one of which is shown at 16. Shaft 14 is driven by a suitable motor, not illustrated. Housing 10 comprises a pair of side walls 18, 20, a rear wall 22 and a front cover section 24. The upper end of housing 10 is reinforced by a rectangular angle iron frame 26 which defines the upper end of the inlet hopper 28 of the hammer mill. In most instances, a chute 30 will be mounted on housing 10 to communicate with inlet opening 28. Preferably, the rear wall 22 has a replaceable wear plate 32 attached to the inner side thereof.

The lower end of the housing includes a discharge chute 34 which is defined by the two side walls 18, 20 of the housing, at the front by a short inclined wall 35 and at the rear by two oppositely inclined walls 38, 40. At the upper end of wall 40, the housing is reinforced by a solid cross bar 42 anchored at each end on the side walls of the housing. Referring specifically to FIG. 1, the front edges of side walls 18, 20 are inclined upwardly and rearwardly and are flanged as by means of angle irons 44 which provide supports to which the cover 24 may be secured as by screws 46.

The specific rotor 12 shown in the drawings comprises a plurality of spaced discs 48 which pivotally support around their periphery a plurality of hammers 50. This form of rotor is shown merely for purposes of illustration, the invention in its broader aspects employing a rotor of any conventional form.

Referring to FIG. 2, it will be noted that the housing 10 around the periphery of rotor 12 comprises generally three portions; namely, an inlet portion defined by the inlet hopper section 28, the cover portion 24 and around the lower side of the rotor, the outlet portion which establishes communication between the rotor chamber 52 and the discharge chute 34. This outlet portion is covered by a screen 54. Screen 54 is formed from a rigid as distinguished from a flexible material and retains the shape

2

illustrated in the drawings. Screen 54 is located and positioned in the housing along its radically inner side by a pair of guide rails 55, one on each side wall of the housing. Around its radically outer side, screen 54 is located and supported by a cradle 58. Cradle 58 comprises a plurality of four axially spaced circular segment bars 60 which are interconnected by a plurality of cross bars 62. Cradle 58 is pivotally supported on the two side walls of housing 10 by threaded studs 64. The cradle is designed to be pivotally actuated by rotating a handle 66 (FIGS. 1 and 4) fixed to a rock shaft 68 journalled on the side walls of housing 10. At approximately the center thereof, shaft 68 has a short link 70 fixed thereto as by welding. The free end of link 70 is pivotally connected as at 71 with a longer link 72 which is pivotally supported as at 73 by a bearing block 74. Block 74 is welded or otherwise fixed on a flat cross bar 76 which interconnects the lower or free ends of the circular segment bars 60 of the cradle.

20 In FIG. 2, the toggle linkage formed by the links 70, 72 is shown in the locked position wherein the handle 66 is pivoted downwardly to its lowermost position so that the links 70, 72 urge the bar 76 and the spaced bearing blocks 73 secured thereto upwardly in a counterclockwise direction as viewed in FIG. 2. It will be noted that the forward edge of screen 54 is in end abutting relation as at 80 with the lower edge of cover 24. This forward edge of the screen has a handle 82 bolted thereon, the handle being in the form of an angle iron. The handle projects outwardly beyond the end of the screen and thus, in the locked position of the screen, overlaps the lower edge of cover 24. Thus, in the locked position of the toggle linkage 70, 72, cross bar 76 with its bearing blocks 73 bears upwardly against handle 82 to form a tight sealed connection between the screen handle 82 and cover 24. It will also be observed that the end portion 84 of each inner screen guide 55 is located slightly radially inwardly relative to the remainder of the screen guide so that the pressure exerted by the toggle linkage 70, 72 is utilized exclusively in forming a tight sealed connection between the screen handle 82 and cover 24. It is to be understood, of course, that the linkage 70, 72 is permitted to shift to the over-center locked position illustrated in FIG. 2 by reason of the flexing of shaft 68.

45 Referring to FIGS. 2 and 4, the end of shaft 68 opposite handle 66 is journalled in the side wall 20 of housing 10 in a hole 86 which is generally the same diameter as shaft 68. However, in order to withdraw rock shaft 68 from within the housing for servicing with the short link 70 welded thereto, the side wall 18 of the housing has an aperture 88 slightly larger than link 70. This end of the rock shaft 68 is journalled on a bearing plate 90 which is bolted to side wall 16, the holes 92 for the bolts being elongated slightly as shown in FIG. 2 so as to permit adjustment of the locking pressure when handle 66 is actuated. Rock shaft 68 is fixed against lengthwise shifting by bushings 93.

Still referring to FIG. 2, it will be observed that the radially outer ends of hammers 50 are located relatively close to the inner surface of cover 24 and the inner surface of screen 54. It is necessary that the ends of those hammers travel in a circular path relatively close to the cover and the screen so that there will be little or no tendency for the holes in the screen to become plugged.

60 The fineness of the finished product is regulated by the size of the holes in the screen. For fine grinding or pulverizing grain, a screen with small holes will be employed and unless the screen is spaced closely to the path of travel of the ends of the hammers on the rotor, the holes in the screen will tend to become plugged.

In the machine of this invention, cover 24 is concentric with the axis of the rotor shaft 14. However, in order to

obtain the maximum size screen and in order to permit this screen to be rigid and yet safely removed from the housing, screen 54 is formed as a cylindrical segment which has its axis at 94, shifted slightly from the axis 96 of the rotor shaft upwardly and toward cover 24. Thus, as will be apparent from the showing in FIG. 2, the radius of screen 54 is slightly greater than the radius of cover 24. This difference in radii facilitates removal of the screen from the housing and promotes the maintenance of a large size outlet for the hammer mill.

Referring to FIG. 3, the screen 54 is adapted to be withdrawn from the housing through an opening 98 between the lower end of cover 24 and a plate 100 extending transversely across the housing at the upper edge of the inclined forward wall 36. From the standpoint of safety, the opening 98 should be as narrow as possible. This is true because in many instances, it becomes necessary to change screens in a hammer mill while the rotor is still rotating. Under such condition of operation, it is desirable to have any opening in the hammer mill housing as small as possible so that the likelihood of the operator being struck by any particles, etc. discharged by the rotor through the screen outlet is minimized. In the particular arrangement illustrated in the drawings, the width of opening or slot 98 is minimized by making the radius of screen 54 slightly greater than cover 24. However, the pulverizing action is not sacrificed in any way because the cradle 58 is designed to position the screen 54 with its axis at 94 so that it is in end abutting relation with the cover 24 and extends generally as a continuation of the circle defined by cover 24. The screen is thus located closely adjacent the path of travel of the outer ends of the hammer 50 on the rotor.

To withdraw the screen from the housing, it is only necessary to pivot handle 66 upwardly to the broken line position shown in FIG. 3 and then rotate the screen out of opening 98. When handle 66 is rotated to the unlocked position, it will be observed that cradle 58 pivots downwardly about its pivot support at 64 so that the screen 54 is released from its clamped position. Then, by drawing upwardly and slightly forwardly on the screen handle 82, the operator can withdraw the screen 54 through the opening 98 and slide it over the outer surface of cover 24. Since the screen has a slightly larger radius than cover 24, the screen more or less rides snugly against the outer surface of cover 24 as illustrated by the broken line showing at 102 in FIG. 3. It will be appreciated that to accomplish this withdrawal of the screen, it is only necessary that the slot 98 have a width only slightly greater than the thickness of the screen at the handle end as increased by the heads of the screws 104 which secure the handle 82 to the screen. To facilitate complete removal of the screen from within the housing, the upper end of cover 24 is fashioned with a tapered rib 106. When the screen 54 is shifted upwardly to the position shown in full lines in FIG. 3, the upper end of the screen is raised out of contact with the cover 24 so that the operator may grasp the screen firmly at its opposite edges to completely lift it out of the housing through slot 98.

The screen may be replaced by simply reversing the operation described; namely, initially positioning the screen as shown in solid lines in FIG. 3 and thereafter progressively revolving it in a clockwise direction between the inner guide 56 and the arcuate bar 60 of the cradle until it assumes a position wherein the handle 82 engages the flat bar 100. Thereafter, handle 66 is pivoted downwardly in a clockwise direction as viewed in FIGS. 2 and 3 to clamp the screen in place as illustrated in FIG. 2. With the screen locked in place, it will be observed that the slot 98 is completely closed by handle 82, cross bar 76 and the flexible sealing strip 108 secured to cross bar 76 and adapted to engage the inner side of bar 100 when the screen is locked in its operative position by the toggle linkage.

The sealing engagement of strip 108 may be enhanced

by a felt strip 110 on the inside of bar 100. Likewise, the proper engagement of the toggle operated lock may be facilitated by relieving the screen engaging face of blocks 78 as at 112.

Thus, it will be seen that the hammer mill of this invention possesses several desirable features. The design of the machine is such that the screen can be removed from its operative position through a relatively narrow opening in the housing without requiring flexing of the screen. Thus, the screen is adapted to be made from a rigid material so as to be capable of handling heavy loads. At the same time, the screen is designed so that it is fairly concentric with the axis of rotation of the rotor and positioned closely adjacent the path of travel of the ends of the rotor. In view of this specific arrangement, a reasonably narrow slot for the removal of the screen can be provided and the operator will therefore not be subjected to hazardous conditions when the screen is removed.

I claim:

20. 1. A hammer mill comprising a housing having a hammer mill rotor journaled for rotation therein on a horizontal axis, said housing being divided generally into three portions around the periphery of said rotor, namely, an inlet portion through which the material to be processed 25 is directed to the rotor, an outlet portion through which the process material is discharged and a peripherally closed portion, said peripherally closed portion comprising a generally cylindrical cover portion extending around and closely adjacent the outer periphery of the rotor, a 30 generally rigid cylindrically shaped screen covering said outlet portion, said screen at one end being circumferentially contiguous to one end of said cover portion of the housing and having a radius slightly greater than the radius of said cylindrical cover portion, said screen extending 35 across said outlet opening closely adjacent the periphery of the rotor and being eccentric with respect to the axis of rotation of the rotor when in operative position, said housing having a narrow, horizontally extending opening therein adjacent the circumferentially contiguous ends of said screen and said cover portion, said screen having a handle portion projecting through said opening and the opening enabling the screen to be withdrawn therethrough in an arcuate path overlying the outer 40 arcuate surface of the cylindrical portion of the housing and having a width only substantially sufficient to permit such withdrawal of the screen.

2. A hammer mill as called for in claim 1 wherein one end of the screen abuts circumferentially in end to end relation against the adjacent end of the cover portion of the housing, said adjacent ends of the screen and cover portion having a generally common tangent, and including means for locking said screen in said position.

3. A hammer mill as set forth in claim 1 wherein the 55 circumferential extent of said screen is at least as great as the circumferential extent of said cover portion of the housing.

4. A hammer mill as set forth in claim 1 wherein the circumferential extent of said screen is at least as great as the circumferential extent of said inlet opening and at least as great as the circumferential extent of said cover portion of the housing.

5. A hammer mill comprising a housing having a rotor journaled therein, said housing having a discharge chute extending from the periphery of the rotor, said discharge chute being closed at the periphery of the rotor by a screen, said screen being formed generally as a segment of a cylinder and being rigid as distinguished from flexible, said housing having a cylindrical wall circumferentially adjacent one end of the screen and forming an arcuate extension of said screen, said screen having a radius slightly larger than the radius of said cylindrical wall, and when in the operative position being slightly eccentric with respect to the axis of rotation of the rotor, said housing having a narrow opening adjacent the adjoining ends 70 of the screen and cylindrical side wall through which the 75

screen may be withdrawn, said opening having a width substantially only sufficient to permit the screen to be withdrawn from the housing by revolving the screen outwardly through said opening and over the outer surface of said cylindrical side wall.

6. A hammer mill as called for in claim 5 including a cradle extending around and supporting said screen, said cradle being pivotally supported at one end adjacent the opposite end of said screen when in operative position and means connected with the other end of said cradle for actuating the cradle and locking the screen in said operative position, said locking means including a sealing member which, when the locking means are in the locked position, engages a portion of the housing and cooperates with the screen to seal said opening.

7. A hammer mill as called for in claim 5 wherein said one end of the screen and the adjacent end of said cylindrical wall are in end to end abutting relation, and the screen is positioned such that it forms a smooth continuation of curve established by the cover.

8. A hammer mill as called for in claim 5 wherein said cylindrical wall is generally concentric with the axis of rotation of the rotor and wherein the center of curvature of the screen when in operative position is offset from the axis of rotation of the rotor in a direction away from said screen and toward said cylindrical wall.

9. A hammer mill as called for in claim 5 wherein said screen has a handle portion extending through said opening.

10. A hammer mill as called for in claim 9 wherein said cylindrical wall has an inclined rib member thereon adjacent the end thereof remote from said opening for raising the handle end of the screen from the outer surface of the cylindrical wall as the handle end of the screen approaches said remote end of the cylindrical wall.

11. A hammer mill as called for in claim 5 including means for locking said screen in its operative position, 10 said locking means including a sealing member which, when the locking means are in locked position, engages a portion of the housing and cooperates with the screen to seal said opening.

12. A hammer mill as called for in claim 5 wherein 15 the screen has a circumferential extent at least as great as the circumferential extent of said cylindrical wall.
